UNITED STATES PATENT OFFICE.

DAVID G. SMYTH, OF HARTFORD, CONNECTICUT.

APPARATUS FOR DEMONSTRATING GRAVITY ACCELERATION.

Application filed April 6, 1925. Serial No. 21,156.

To all whom it may concern:

Be it known that I, DAVID G. SMYTH, a citizen of the United States, residing at Hartford, in the county of Hartford and State of Connecticut, have invented a new and useful Improvement in Apparatus for Demonstrating Gravity Acceleration, of which the following is a specification.

One of the problems confronting the teacher of physics is the experimental determination of the acceleration due to gravity. This invention relates to an apparatus for graphically illustrating a factor of such problems.

The object of the present invention is to provide a simple and inexpensive apparatus by means of which the distance traversed by a freely falling body in a known interval of time is registered mechanically with directness and accuracy upon a concrete object such a ribbon, tape, cord or the like.

In the accompanying drawings Fig. 1 is a perspective view of an apparatus that embodies the invention. Fig. 2 shows a recording strip which has been passed through the apparatus and cut during a demonstration. Fig. 3 shows a different way of marking the strip. Fig. 4 shows a modified construction of the apparatus.

The structure illustrated has a vertical frame 1 supported by feet 2. In the first form, shown in Fig. 1, a curved or segmental ledge of metal 3 or other material is attached to the front face of the frame so as to extend outward therefrom. This ledge is permanently fastened to the frame, as by lugs 4 and screw 5. In the second form, illustrated in Fig. 4, this ledge is the perimeter of a wheel 6 rotarily mounted on a stud 7.

Extending downward from the top on the front face of the frame are a pair of ears 8 between which the upper end of a pendulum rod 9 is pivoted by the screw 10. The pendulum is so hung that its plane of oscillation is parallel to the face of the frame adjacent to the outer edge of the ledge. A weight 11 is adjustable upon the pendulum rod, being held by a screw 12 in the position to which it is set. The lower end of the pendulum rod may be bent inward, as shown

in Fig. 1, and provided with a knife or pointed blade 13. The blade may be attached as shown in Fig. 1, so as to stand vertically with its cutting edge uppermost, 55 or it may be, as shown in Fig. 4, in the shape of a knife with its edge set horizontally. In both cases the cutting edge or point of the blade is arranged so as to travel in a plane parallel with the plane of oscillation of the pendulum. If desired, instead of a blade which will cut or tear the strip, a pencil 14 or similar marking means may be attached to the pendulum, as illustrated in Fig. 3.

An anvil block 15 preferably of wood, is attached to the frame so that its face 16 is parallel with and adjacent to the vertical plane which is tangent to the ledge. The block may be pivotally held by a screw 17 60 so the block may be swung to one side, into a position where it will not interfere with the free oscillation of the pendulum, as shown by dotted lines in Fig. 1. The face of this block is desirably provided with an index mark, which may be a horizontal line 18. A stud 19 is set into the frame to form one limit for the oscillation of the pendulum.

In making use of this apparatus to determine the acceleration due to gravity, the 65 frequency of oscillation of the pendulum is ascertained by any of the well known methods, preferably by counting the number of oscillations in a known interval of time. A ribbon of paper 20, Fig. 1, or cord 21, 70 Fig. 4, or other light material, is laid around the band. One end of this flexible ribbon or cord is connected with the lower end of the pendulum rod. A plummet 22 is attached to the other end of the ribbon or 75 cord below the anvil block. The mass of the plummet is sufficiently great to, acting through the ribbon or cord, retain the pendulum against the stop stud. When this ribbon or cord is severed adjacent to the 80 plummet, as it may be by any suitable means, the plummet drops and draws the ribbon or cord over the ledge and past the anvil block.

Coincidently the pendulum 85 swings away from the stop toward the block 100 until the point or edge of the knife blade reaches and pierces or severs the down-

wardly drawn strip, or the pencil marks the strip. Before the connection between the ribbon and the pendulum is severed, however, it is necessary that a reference line 23 5 preferably horizontal be marked on the ribbon opposite the index line on the block or the cord be marked at the same point. The index line and the reference line are in the position which the point or blade of the 10 knife or point of the pencil would strike the ribbon, when the pendulum is swung one-half of an oscillation with the ribbon at rest. The distance from the reference line on the ribbon or cord to the point of puncture or severance of the ribbon or cord by 15 the blade is the distance through which the plummet has fallen during the interval of one-half of the oscillation of the pendulum. This distance and the factor of frequency 20 of the pendulum are then used in the well known equation. ($S = \frac{1}{2}gt^2$) to give the answer to the problem, or the acceleration due to gravity.

By making use of a plummet the mass of 25 which considerably exceeds the mass of the ribbon or cord errors due to the inertia of the ribbon or cord or the friction against the ledge are reduced to a minimum. Should the ledge be rotatable, that is, formed on 30 the rim of a wheel or pulley, the friction is still further reduced. The frequency of oscillation of the pendulum may be varied by changing the position of the sliding weight. The function of the anvil block is to prevent 35 the lateral motion of the ribbon or cord when intercepted by the blade, thus ensuring practically an instantaneous piercing of the ribbon or severing of the cord.

The invention claimed is:—

- 40 1. A gravity acceleration apparatus comprising a frame, a ledge extending outward from the face of the frame, a pendulum supported by the frame and adapted to swing across its face, a plummet, a flexible strip 45 loosely passing over the ledge and having one end connected with the plummet and the other end connected with the pendulum whereby the plummet through said strip temporarily holds the pendulum at one side 50 of the center of its path of oscillation, and means carried by the pendulum and adapted to engage and mark said strip when the latter is severed and the plummet is allowed to drop and the pendulum allowed to swing.
- 55 2. A gravity acceleration apparatus comprising a frame, a curved ledge extending outward from the face of the frame, a pendulum supported by the frame and adapted to swing across its face, a plummet, a flexible strip 60 loosely passing over said ledge and having one end connected with the plummet and the other end connected with the pendulum whereby the plummet through said strip temporarily holds the pendulum at one side 65 of the center of its path of oscillation, and means carried by the pendulum and adapted to engage and

and means carried by the pendulum and adapted to engage and mark said strip when the latter is severed and the plummet is allowed to drop and the pendulum allowed to swing.

3. A gravity acceleration apparatus comprising a frame, a ledge rotarily attached to the face of the frame, a pendulum supported by the frame and adapted to swing across its face, a plummet, a flexible strip loosely passing over said ledge and having one end connected with the plummet and the other end connected with the pendulum whereby the plummet through said strip temporarily holds the pendulum at one side 70 of the center of its path of oscillation, and means carried by the pendulum and adapted to engage and mark said strip when the latter is severed and the plummet is allowed to drop and the pendulum allowed to swing.

4. A gravity acceleration apparatus comprising a frame, a ledge extending outward from the face of the frame, a pendulum supported by the frame and adapted to swing across its face, a plummet, a flexible strip loosely passing over the ledge and having one end connected with the plummet and the other end connected with the pendulum whereby the plummet through said strip temporarily holds the pendulum at one side 75 of the center of its path of oscillation, a marker carried by the pendulum and adapted to engage said strip when the latter is severed and the plummet is allowed to drop and the pendulum allowed to swing, and an anvil 80 block mounted on the frame in the path of oscillation of said marker.

5. A gravity acceleration apparatus comprising a frame, a ledge extending outward from the face of the frame, a pendulum supported by the frame and adapted to swing across its face, a plummet, a flexible strip loosely passing over the ledge and having one end connected with the plummet and the other end connected with the pendulum 90 whereby the plummet through said strip temporarily holds the pendulum at one side of the center of its path of oscillation, and a knife blade carried by the pendulum and adapted to engage said strip when the latter is severed and the plummet is allowed to drop and the pendulum allowed to swing.

6. A gravity acceleration apparatus comprising a frame, a ledge extending outward from the face of the frame, a pendulum with an adjustable weight supported by the frame and adapted to swing across its face, a plummet, a flexible strip loosely passing over the ledge and having one end connected with the plummet and the other end connected with the pendulum whereby the plummet through said strip temporarily holds the pendulum at one side 95 of the center of its path of oscillation, and means carried by the pendulum and adapted to engage and

mark said strip when the latter is severed and the plummet is allowed to drop and the pendulum allowed to swing.

7. A gravity acceleration apparatus comprising a frame, a pendulum supported by the frame, a marker carried by and swinging with the pendulum, a flexible

connection between the plummet and pendulum, and means temporarily holding said connection with its weighted end in the path of oscillation of the marker carried by the pendulum.
